(57) **CLAIM**

The ornamental design for a stabilisation ring segment for an underground reamer, as shown and described.

DESCRIPTION

FIG. 1 is a top view of a first embodiment of a stabilisation ring segment for an underground reamer;

FIG. 2 is a left side view thereof;

FIG. 3 is a front view thereof;

FIG. 4 is a right side view thereof;

FIG. 5 is a bottom view thereof;

FIG. 6 is a front perspective view thereof;

FIG. 7 is a rear perspective view thereof;

FIG. 8 is a top view of a second embodiment of a stabilisation ring segment for an underground reamer;

FIG. 9 is a left side view thereof;

FIG. 10 is a front view thereof;

FIG. 11 is a right side view thereof;

FIG. 12 is a bottom view thereof;

FIG. 13 is a front perspective view thereof; and,

FIG. 14 is a rear perspective view thereof.

The second embodiment of the stabilisation ring segment for an underground reamer is shown with a symbolic break in its length. The appearance of any portion of the article between the break lines forms no part of the claimed design.
